UNITED STATES PATENT OFFICE

JOSEPH H. CLEMENTS, JR., OF SCHENECTADY, NEW YORK, ASSIGNOR TO PECKHAM, WOLF & CO., OF SCHENECTADY, NEW YORK, A CORPORATION OF NEW YORK

ARTICLE OF FURNITURE

Application filed November 2, 1929. Serial No. 404,358.

The present invention relates to improvements in furniture, and has for its object to provide an article which may be used for various purposes. By the invention I provide an article adapted to serve as either a table, a stool or seat, and a step-ladder, the several parts being so arranged as to provide an attractive and neat appearing article of furniture which can be readily adjusted to serve 10 any of the several purposes for which it is adapted.

With the foregoing and other ends in view, the invention consists in the construction and arrangement of parts that will be herein- 15 after described and claimed in connection with the accompanying drawings, in which:

Figure 1 is a perspective view of an embodiment of the present invention showing the parts positioned to serve as a step-ladder. 20 Figure 2 is a vertical section with the parts in a different relation from that shown in Figure 1.

Figure 3 is a section substantially on the line 3—3 of Figure 2.

25 Figure 4 is a perspective view of a portion of the article with the stand member thereof detached.

Referring to the drawings, in the several views of which like parts are designated by 30 corresponding reference characters, the improved article of furniture comprises a main body including a top 1, shown as being of substantially rectangular form, and suitable supports or legs 2.

25 In the embodiment of the invention illustrated, in which, as noted, the top 1 is of rectangular form, there are four legs 2, and these are connected by parallel end frames 3 and a rear frame member 4.

40 As shown, the end frame members 3 are provided on their inner faces with guide rails 5 which are engaged by grooves 6 formed in the outer faces of opposite members of the 45 depending sides of a top 7 of an auxiliary body.

By this arrangement the main and auxiliary bodies are so connected that the auxiliary body may be moved to and from a position 50 in which it will be entirely below the top 1

of the main body or within the space marked by the supporting legs 2 of the main body.

The auxiliary body is shown as having two legs or supports 8 which, when the parts are positioned as shown in Figure 1, are some 55 distance from the adjacent legs 2 of the main body and serve to provide a firm support for the top member 7 so that the latter constitutes a step-like tread of a ladder including the main and auxiliary bodies. 60

The main body is also provided with a slide 10 which is shown as supported by guides 11 so that it may be projected beyond one end of the top 1 of the main body as shown, or can be moved inward so as to be 65 entirely beneath and concealed from view by the top 1.

As shown, this slide 10 is provided with two sockets 10a situated relatively close to the edge of the top 1 when the slide is projected 70 from the main body and in the outer edge of said slide is formed a notch 12.

A stand comprising a top 13, two relatively short supports 14, and a relatively long support or standard 15, is adapted to be engaged 75 with the sockets 10a and notch 12 of the slide 10 to provide a stand at one end of the top 1 of the main body which, when the article is being employed as a step-ladder, for example, may serve as a support for a pail or other 80 receptacle.

Preferably, as shown, the supports 14 and 85 15 are connected by hinges 16 with the top 13 so that when the stand is detached the supports may be folded against the top 13 and in its collapsed form the stand will occupy a minimum amount of space.

The shorter supports 14 are shown as being reduced in size at the lower ends to fit in the sockets or apertures 10a and a latch or hook 90 17 is provided for retaining the longer support 15 within the notch 12.

To strengthen the construction when the stand is in use, a spring brace 20 is shown as connected with the longer support or upright 95 15 and the spaced ends thereof are adapted to be engaged with suitable sockets or fittings on legs 2 of the main body.

It is believed that the advantages and uses 100 of the improvements will be readily under-

stood from the foregoing description and the drawing. When the stand is detached and the slide 10 and auxiliary body are in position beneath the top 1 of the main body, a neat and strong table is provided which can be used
5 for various purposes.

By making the legs 2 of proper length the table-like article is adapted to serve as a seat or stool for use in a kitchen or at the end of a "breakfast nook", for example.

10 By adjusting the main and auxiliary bodies into the relative positions shown in Figure 1, a strong step-ladder is provided, and by the addition of the detachable stand a pail or
15 other utensil can be securely supported in position for easy access by a person using the ladder.

When it is desired, the collapsible stand can be easily detached and, as before noted,
20 its parts folded so that it will occupy a minimum amount of space.

I claim:

1. A combined seat and step-ladder comprising a main body including a top and suitable legs, an auxiliary body including a step-tread member, connected with the main body and bodily movable to and from a position beneath the top of the main body, a stand arranged at one end of the main body and consisting of a top and a plurality of uprights depending from said top, and independent of the legs of the main body, one of said uprights being detachably connected to the main body and another extending to the floor on which the main body stands, and a brace detachably connecting the last said upright with two of the legs of the main body.

2. A combined seat and step-ladder comprising a main body including a top, suitable legs, a step tread bodily movable to and from a position beneath the top and a slide adapted to be projected from one end of the body beneath the top thereof, and a stand comprising a top and a plurality of uprights depending from said top, one of said uprights having its lower end detachably engaging said slide and another extending past said slide to the floor on which the main body stands.

3. A combined seat and step-ladder comprising a main body including a top, suitable legs and a slide adapted to be projected from one end of the body beneath the top thereof, said slide having a recess or notch formed in its outer end, and a stand comprising a top and a plurality of uprights depending from said top, one detachably engaging said slide and another extending through said notch in the slide to the floor on which the main body stands.

60 In testimony whereof I have hereunto set my hand.

JOSEPH H. CLEMENTS, JR.
